UNITED STATES PATENT OFFICE.

ALBERT BRIOT, OF PARIS, FRANCE.

COP-CHANGING MECHANISM FOR LOOMS.

1,198,615.

Specification of Letters Patent. Patented Sept. 19, 1916.

Application filed July 19, 1911. Serial No. 639,286.

To all whom it may concern:

Be it known that I, ALBERT BRIOT, citizen of the French Republic, residing at Paris, in the Department of the Seine, France, have invented certain new and useful Improvements in Improved Cop-Changing Mechanism for Looms, of which the following is a specification.

The present invention relates to mechanism for the automatic changing of the cops in ordinary weaving looms and of the type described in my previous British Patents Nos. 13,831 of 1904 and 3758 of 1907, and has for its object further improvements in such mechanisms, more particularly as regards: 1, the manner in which the cop is held on the transferrer; 2, the mechanism for effecting a certain ejection of the empty cop; and 3, the means for insuring rigidity 20 of the transferrer when the shuttle is in correct position for the change.

The invention consists in an improved cop changing mechanism of the type above referred to, in which the point of the cop to be transferred is held in a groove or channel at the end of one arm of the transferrer where this point is hooked by a dog pivoted on the said arm, at the beginning of the rotary movement of the transferrer and the cop caused to simultaneously slide axially, while the heel of the cop rests on a second arm of the transferrer carrying a fixed spur adapted to engage in a recess in the heel of the cop when the axial movement 35 of this latter occurs.

The invention also consists in an improved method of expelling the empty cop by means of an inclined guard on the cop gripping tongs, a movable finger forming part of the transferrer, and teeth on the tongs, substantially as hereinafter described.

The invention further consists in improved means for holding the normally flexible transferrer rigid while the cop is being inserted in the shuttle, these means comprising a finger on the second arm of the transferrer, which finger places itself under a member on the transferrer spindle when a projecting finger on the first arm of the transferrer encounters an inclined stop, substantially as hereinafter described.

These various improvements in the mechanism for changing the cops are illustrated

in the drawings accompanying this specification, in which:

Figure 1 is a front view of the transferrer in the position of receiving a cop from the magazine; Fig. 2 is a plan view illustrating the transferrer and the shuttle box 60 during the changing, the shuttle being indicated diagrammatically and the upper face thereof being assumed as removed to enable all the details to be seen; Fig. 3 is a plan view of the weft stop motion and the mechanism effecting the changing and the stopping of the loom; Fig. 4 is a side view of the arm of the transferrer supporting the points of the bobbins; Fig. 5 is a side view of the arm of the transferrer supporting 70 the heel of the bobbins; Fig. 6 is a section through the center line of the arm 10; Fig. 7 illustrates the relative position of the heels of two cops at the instant when they come in contact; Fig. 8 is a front view of 75 the gripping tongs; Fig. 9 is an end view thereof; Fig. 10 is a modification of the method of locking the transferrer; Fig. 11 is a side view of the transferrer showing the same deflected owing to an incorrect 80 position of the shuttle in the box.

According to these figures and assuming the mechanism to be attached to the breast beam of an ordinary weaving loom, facing the shuttle box opposite the weft stop motion, there is seen fixed to the said breast beam a frame 1 (Figs. 1 and 2) comprising two vertical standards on which are bolted two slides 2, 3 (Fig. 1) constituting the magazine, at the lower end of which are 90 arranged two pins 4, 5, thrust out by springs, the object of which is to prevent the cops contained in the magazine from falling when the transferrer is in the position of changing. This transferrer is constituted of a spindle 6 parallel to the slay, capable of rotating in two bearings formed in the frame 1, and carrying three arms 7, 7', 7'', which are perpendicular to the spindle 6 and support a rod 8 parallel to spindle 6 (Figs. 1 and 2). This rod serves as pivot for a cop carrier constituted of two bent arms 9 and 10 connected by a cross rod 11 (Figs. 1, 2, 4, 5 and 11), the arm 9 being extended in a finger 11' the function of which 105 will be hereinafter explained. This assemblage constitutes a kind of elastic knee piece (Figs. 4, 5 and 10) and the cop carrier

is capable of longitudinal sliding movement on the rod 8. For this purpose the arm 9 has a sleeve 14, on which is pivoted a lever 13 carrying a stop 15. The other end of this lever engages in a groove 17 formed longitudinally in the spindle 6. A spring 12 is attached at one end to the stop 15 and at the other to the sleeve 14, so that it tends continually to open the knee piece. The amount of opening is limited by the opposition of the stop 15 and another stop 16 forming part of the arm 9.

The arm 10 of the cop carrier is situated between the arms 7, 7'. A spring 17' carried by the rod 8 and abutting at one end against the sleeve 14 and at the other against the arm 7' tends to force the cop carrier against the arms 7 and 7' (Fig. 1).

The cop 18 to be transferred rests on the ends of the arms 9 and 10 of the cop carrier and is held there in the following manner. At the end of the arm 9 is formed a groove or channel in which is placed the point of the cop 18. In the axes of this arm is formed a groove 19 in which can pivot a dog 20 acted on by a spring 21 (Figs. 1, 2, 4 and 11). The arm 10 on the end of which rests the heel of the cop 18, carries a fixed spur 22 (Figs. 1, 2, 5, 6) which, in a manner to be subsequently explained, can place itself in the recess of the heel of the cop as shown in Fig. 6. A finger 24 in which is formed a longitudinal groove for receiving the spur 22, is jointed at 23 to this spur (Figs. 1, 2, 5, 6 and 7). The amplitude of its oscillation is sufficient to enable it to mask or completely uncover the spur 22. The finger is recessed circularly for a part of its thickness so as to form a channel indicated in sectioning (Fig. 5) enabling it to receive the heel of a cop (Figs. 1, 2 and 7).

The slide 2 carries an adjustable piece 25 (Figs. 1 and 4) of horizontal channel section, the lower arm of which is adapted to release the dog 20 from the bend 59 of the spring 21, and the upper arm to stop it in a position enabling a bobbin to drop from the magazine on to the cop carrier (Fig. 1).

The working of the transferrer is effected by means of a spindle 26 parallel to the breast beam and running the length of the loom. This spindle can oscillate in two supports fixed to the frame of the loom. At the end adjacent to the cop changing mechanism is fixed a lever 27 carrying at its other end a pivot adjustable in a slide and serving as a joint member for a chain 28, the other end of which is jointed to an arm 28' attached to the spindle 6. This lever 27 also carries a spring 29 the purpose of which is to restore the transferrer to the receiving position after the changing (Figs. 2, 4 and 16).

The part of the shaft 26 adjacent to the weft stop motion carries a bent lever 30, the

end 31 of which can come into engagement with a pawl 32, carried by the fork holder rod of the weft stop motion (Fig. 3).

As regards the cops and cop carriers employed in this mechanism they are of the ordinary type, but comprise a cylindric heel provided with a ring of greater diameter (Figs. 1, 2, 6 and 7). In the center of this heel is formed a circular recess shown in section in Fig. 6, adapted to receive the spur 22 (Fig. 6).

As regards the shuttle, this comprises:

Gripping tongs of well known type having an inclined guard 48 (Figs. 2 and 7). These tongs are provided on each arm with a circular groove to receive the ring of the bobbin and at its open end with four teeth 49, 50, the object of which will be subsequently pointed out (Figs. 2, 7, 8 and 9). The position of the guard 48 in the tongs is such that the distance from its ends to the rear face of the heel of the cop 18 placed in the tongs is equal to the thickness of the finger 24 as shown in Fig. 2. An inclined piece 51 is inserted in the opening in the shuttle at the end thereof opposite the guard 48. This incline is directed in the opposite direction to that of the tongs and has a part 52 perpendicular to the axis of the shuttle. The distance from the part 52 to the point of the guard 48 is equal to the total length of the cop carrier when the finger 24 masks the spur 22 as shown in Figs. 1 and 2.

Operation: When the weft thread is missing in front of the fork the rod 34 is drawn back. The pawl 32 comes into engagement with the lever 30, the shaft 26 rotates lifting the lever 27 which produces slackening of the chain 28. Under the action of the spring 53 (Fig. 2) the transferrer becomes lowered until the cop which it carries arrives opposite the opening of the shuttle case. At the beginning of the rotary movement of the transferrer the dog 20, freed by the action of the piece 25, hooks the point of the cop 18 under the action of the spring 21, at the same time causing it to slide along its axis so that the spur 22 moves into the recess in the heel of this cop (Fig. 6) which is thus firmly held. An inclined piece 54 (Fig. 11) fixed to the slay, guides the transferrer.

The shuttle having arrived in the shuttle box, two conditions may arise: 1. It may not be positioned in the extreme end of the shuttle box; the finger 11' meeting this shuttle, the transferrer gives way, the loom continuing to rotate and the transferrer rises without having released the cop which it carries; the weft stop motion is again actuated but it merely stops the loom as will be hereinafter explained; 2, the position of the shuttle may be such that the slay continuing to advance the finger 11' encounters

- the incline 51. The cop carrier slides on the rod 8; a finger 55 on the arm 10 places itself underneath a member 56 attached to the spindle 6 (Fig. 2). The transferrer is thus held rigidly. When the end of the finger 11' has passed the incline 51 the heel 18 encounters in the position shown in Fig. 7 the heel of the cop 57 to be expelled and releases it from the groove in the tongs.
- 10 At this instant the finger 24 comes in contact with the guard 48 and pivots, at the same time pushing the heel 18 so as to release it from the spur 22. During this movement the rings of the two heels have
- 15 come into contact and the cop 57 of which the longitudinal movement is prevented by the teeth 49 (Figs. 2, 7, 8 and 9) of the tongs is obliged to take up a rotary movement in the direction of the arrow (Fig. 2).
- 20 It is then expelled, the point foremost. The slay continuing to advance, the cop 18 takes the place of cop 57 when the slay is at the end of its forward stroke.
- The teeth 50 of the tongs serve the purpose of guiding the heel of the cop 18 and of preventing it from passing in front of the tongs. During the period of expulsion of the bobbin 56 the end of the dog 20 has come into contact with the striking cheek
- 25 58 which causes it to turn so as to release the point of the cop 18, the end of the dog then placing itself in the bend 59 of the spring 21 so that the dog 20 remains open when the slay moves back.
- 30 35 The length of the incline 51 being limited by the dimensions of the shuttle, with a view to increase the length of the region occupied by the shuttle within which changing is possible, the transferrer is regulated so that
- 40 45 when the shuttle is positioned in the end of the shuttle box there is a certain play between the finger 11' and the part 52 of the inclined piece 51. The shuttle is thus too distant for the changing, but at the instant that the end of the finger 11' arrives in front of 52, the shuttle is pushed toward the interior of the loom by means of a lever 60 pivoted on a pin fixed to the frame, acting behind the picker and driven by an inclined and regulable member 61 fixed on the spindle 6 of the transferrer (Fig. 2). The amplitude of the oscillation of this lever is such that if the hole produced by the point of the shuttle in the picker is not too deep,
- 50 55 the cop carrier will be pushed back in such a manner that the finger 55 will come under the member 56 which will insure rigidity of the feeder and consequently a correct changing.
- 60 65 From the foregoing description it is seen that the change can only be produced if the shuttle occupies a certain region in the shuttle box; and that the feeder gives way either when the shuttle has not arrived within this region or when it has passed beyond it,

which obviates the damage which would undoubtedly occur if the feeder were kept rigid.

When the replacement is correctly performed, the fork of the weft stop motion is returned by the action of the spring 36 at the same time that the parts of the cop carrier 9, 10, 11, respectively pushed by the spring 17, resumes the position of Fig. 1, and the transferrer rises under the action of the spring 29, pushing the pins 4 and 5 to permit a new cop from the magazine to fall upon the transferrer, which is accomplished by the angularly disposed ends of the pins being struck by portions of the frame of the cop carrier. By this same movement and simultaneously the end of the dog 20 is acted on and comes into contact with the lower arm of the member 25 which frees it from the bend 29 of spring 21, while the upper end holds it sufficiently open to enable a new cop from the magazine to fall on the feeder.

Fig. 10 illustrates a modification of the device for locking the feeder. In this modification the arm 10 of the feeder instead of being straight has a heel 62 which after the sliding of the cop carrier on its spindle 8 will arrive in front of an arm 63 which is adjustable and attached to the frame 1. The purpose of this heel is to prevent the feeder from yielding at the time of the change.

It is evident that modifications may be applied in the arrangement and constructive details of the constituent members of the above described automatic mechanism for the changing of the cops, without exceeding the scope of the invention, the sole object of such modifications being to assist in the perfecting of the whole device and its better operation.

Having now particularly described and ascertained the nature of my said invention and in what manner the same is to be performed, I declare that what I claim is:

1. In looms, an automatic cop changing mechanism comprising a cop carrier support, a cop carrier comprising two arms, one of said arms having a groove therein for the reception of the point of a cop and the other of said arms having a fixed spur adapted to enter a recess in the heel of said cop, a pivoted dog for holding the point of said cop in place in said groove, means for rotating said carrier, means co-operating with said last-named means for moving said dog into its operative position at substantially the beginning of the rotary movement of said carrier and for displacing said carrier in the direction of its axis of rotation at substantially the beginning of said rotary movement.

2. In looms, an automatic cop changing mechanism comprising a cop carrier support, a cop carrier having a groove in one

portion thereof adapted for the reception of the point of a cop, said carrier also having a spur adapted to enter a recess in the heel of said cop, means for displacing said cop longitudinally with respect to said carrier and into engagement with said spur, means for rotating said carrier, means for displacing said carrier in the direction of its axis of rotation, and means for masking 5 said spur prior to the displacement of said carrier in said direction.

3. In a loom, the combination of a shuttle having cop gripping tongs, mechanism for feeding the cops to said shuttle, said cop 10 having a heel provided with an annular ring which is engaged by the cop gripping tongs, a cop carrier support, a cop carrier thereon having means for engaging the point and heel of a cop, and means on the shuttle 15 20 adapted to co-act with said carrier for moving the annular ring on the heel of the cop carried by the carrier beneath the ring of the empty cop in the shuttle to force the point of the same from the shuttle and thereafter force the heel of the cop from the cop gripping tongs.

4. In a loom, the combination of a shuttle having cop gripping tongs, mechanism for feeding the cops to said shuttle, said cop 25 having a heel provided with an annular ring which is engaged by the cop gripping tongs, a cop carrier support, a cop carrier thereon having means for engaging the point and heel of a cop, and means on the shuttle 30 35 adapted to co-act with said carrier for moving the annular ring on the heel of the cop carried by the carrier beneath the ring of the empty cop in the shuttle to force the point of the same from the shuttle and there-

after force the heel of the cop from the cop gripping tongs, said last mentioned means including an inclined guard carried by the shuttle to move the cop carrier longitudinally with respect to said shuttle.

5. In an automatic cop changing mechanism, a normally flexible transferrer comprising two arms, means for holding said transferrer rigid when changing cops, said means including a finger carried by one of said arms, a stop plate for engagement with 40 said finger when the transferrer has been displaced, a projection carried by the other of said arms, an inclined stop, and a spindle for said transferrer having a part carried thereby adapted for engagement with said 45 projection when said finger engages said stop and means for displacing the trans- 50 55 ferrer.

6. In an automatic cop changing mechanism, a normally flexible transferrer comprising two arms, means for holding said transferrer rigid when changing cops, said means including a finger carried by one of said arms, a projection carried by the other of said arms, a stop, and a support for 60 65 said transferrer having a part carried thereby adapted for engagement with said projection when said finger engages said stop, said finger and stop having a wedge-acting 70 engagement with each other when in contact.

In testimony whereof I affix my signature in presence of two witnesses.

ALBERT BRIOT.
